UNITED STATES PATENT OFFICE.

EDGAR J. SPEER, OF NEWARK, NEW JERSEY, ASSIGNOR TO CARRIE E. SLEASE, OF HASBROUCK HEIGHTS, NEW JERSEY.

PHONOGRAPH.

1,357,910.

Specification of Letters Patent. Patented Nov. 2, 1920.

Application filed August 14, 1916, Serial No. 114,881. Renewed March 25, 1920. Serial No. 368,696.

To all whom it may concern:

Be it known that I, EDGAR J. SPEER, a citizen of the United States, residing at the city of Newark, Essex county, in the State of New Jersey, have invented certain new and useful Improvements in Phonographs, of which the following is a full, clear, and exact specification.

This invention relates to improvements 10 in talking machines and more particularly to the construction of the tone-arm and the manner of mounting the reproducer thereon, and has for its object to provide a device of this character adapted for use in 15 connection with records having a tone groove formed either with lateral or vertical undulations.

Further, the invention has for its object 20 to provide a tone-arm which is adjustable in the direction of its length.

Further, the invention has for its object 25 to provide a device consisting of a tone-arm and a reproducer which is adjustable into a plurality of playing positions whereby the device is adapted to play records of dif-

ferent types.

Further, the invention has for its object 30 to provide a device consisting of a tone-arm and a reproducer comprising a sound-box having a diaphragm adapted to be vibrated in accordance with the movement of a stylus in which device the sound-box may be 35 adjusted to cause the diaphragm to assume a position substantially tangential with, or at right angles to the convolutions of the tone groove.

Other objects will in part be obvious and in part be pointed out hereinafter.

To the attainment of the aforesaid objects and ends, my invention consists in the 40 novel details of construction, and in the combination, connection and arrangement of parts hereinafter more fully described and then pointed out in the claims.

45 In the accompanying drawing showing an illustrative embodiment of the invention—

Figure 1 is a plan view of the improved tone-arm and reproducer, the reproducer 50 being shown in one of its operative positions;

Fig. 2 is a view in side elevation thereof;

Fig. 3 is a view similar to Fig. 2, the reproducer being shown in the other of its 55 operative positions, and

Fig. 4 is a sectional view taken on the line 4—4 of Fig. 2.

Referring to the drawings 10 represents the casing of the talking machine upon which is mounted a rotatable record support 11 which carries the record 12 in the usual manner. Secured to the top of the casing 10 and extending upwardly therefrom is a tubular supporting member 13 provided at its lower end with an annular flange 14 which extends within an opening formed in the top of the casing 10.

Rotatably mounted within the tubular member 13 and supported by the shoulder 15, formed by the upper surface of the flange 14, is the downwardly bent end 16 of a swinging tone-arm comprising three tubular portions 17, 18 and 19, the portion 18 being pivotally secured at its inner end to the outer end of the portion 17 by pivots 75

20 whereby it may swing in a vertical plane, and the portion 19 being telescopically and rotatably supported within the portion 18, for purposes hereinafter described, and having its outer end, which constitutes the 80 outer end of the tone-arm, inclined in a downwardly direction. The portion 18 of the tone-arm is provided with a longitudinally extending slot 21 having its outer and inner ends communicating with circumferentially extending slots 22, 23 which are of 85 a length substantially equal to half the circumference of the tubular portion 18. A set screw 24 mounted upon the portion 19 of the tone-arm is adapted to engage the 90 slots 21, 22 and 23 for the purpose of limiting the longitudinal and rotatable movement of the portion 19 relatively to the portion 18 of the tone-arm as hereinafter described.

95 The reproducer comprising a sound-box 25 carrying a detachable stylus 26 is provided with a laterally extending socket 27 to receive the downwardly inclined outer end of the portion 19 of the tone-arm whereby the reproducer may be rotated with respect to the tubular tone arm about the longitudinal axis thereof in order to permit the reproducer to be used in connection with records having tone grooves formed with lateral undulations, as shown in Figs. 1 and 2, and also with records having tone grooves formed with vertical undulations, as shown in Fig. 3. Rotary movement of the reproducer in either direction is limited 100 105 110

- by a set screw 28, carried by the outer end of the portion 19 of the tone-arm, and adapted to engage the end walls of a slot 29 formed in the wall of the socket 27. The slot 29 is of such a length that the reproducer may be rotated about the outer end of the portion 19 through an angle of ninety degrees in moving from one of its operative positions to the other thereof.
- 10 Should the reproducer need repairing it may be withdrawn from the outer end of the tone-arm by first removing the set screw 28.

The operation of the device is as follows:-

- 15 If the record to be played has a tone groove formed with lateral undulations the various parts of the device are adjusted to the positions shown in Figs. 1 and 2, the telescopic portion 19 being in its outermost position with the set screw 24 engaging the outer end of the slot 21, and the reproducer being rotated about the outer end of the tone-arm to occupy a position such that the plane of the diaphragm of the sound-box 25 will be substantially tangent to the convolutions of the tone groove of the record, the reproducer being securely held in its adjusted position by tightening the set screw 28. When the parts are thus adjusted the path of the stylus 26, as it travels from the outer groove to the inner groove, will be substantially radial with respect to the record 12, and the diaphragm of the sound-box 25 will be vibrated by the lateral movements of the stylus 26 due to the lateral undulations of the tone groove.

Assuming now that the record to be played has a tone groove formed with vertical undulations, the set screw 28 is loosened and the reproducer is rotated about the outer end of the tone-arm through an angle of ninety degrees in which position the diaphragm of the sound-box 25 will be in a plane at right angles to the convolutions of the tone groove whereby it will be vibrated by the vertical movements of the stylus 26 due to the vertical undulations of the tone groove. The reproducer is secured in its adjusted position by again tightening the set screw 28. When the reproducer is thus rotated the stylus 26 will occupy a position in advance of the position it formerly occupied, as indicated in dotted lines in Fig. 3, owing to the fact that the sound-box is eccentrically positioned with respect to the axis of rotation of the reproducer. It is therefore necessary to move the telescopic portion 19 of the tone-arm to occupy its innermost position, in which position the set screw 24 engages the inner end of the slot 21, in order to bring the stylus 26 into the same position relatively to the record that it occupied when playing a record having a tone groove formed with lateral undula-

tions, so that the path of the stylus will be substantially radial with respect to the record.

In either case, at the completion of the record, the reproducer may be lifted therefrom by reason of the fact that the portion 18 of the tone-arm is pivotally connected to the portion 17 thereof in such a manner as to permit vertical movement thereof.

In either case when it is desired to insert or to remove a stylus the reproducer and the portion 19 of the tone-arm are rotated with respect to the portion 18 thereof through an angle of substantially one hundred and eighty degrees, the set screw 24 riding in either the slot 22 or the slot 23 depending upon whether the telescopic portion 19 of the tone-arm is in its outermost or innermost position. When these parts have been thus rotated the sound-box 24 will be inverted thus bringing the socket which carries the stylus into position to admit of the removal or insertion of the stylus 26.

Having thus described my said invention, what I claim and desire to secure by Letters Patent is:-

1. A device of the character described comprising a tone-arm adapted to be supported upon the casing of a talking machine and comprising telescopic portions whereby one of said portions may be moved in a longitudinal direction relatively to the other thereof to vary the length of the tone-arm, and a sound-box carried by said movable portion, said movable portion being rotatable independently of its longitudinal movement when in either of its adjusted positions, whereby said sound-box may be inverted to permit the insertion or removal of a stylus when said movable member is in either of its adjusted positions, substantially as specified.

2. A device of the character described comprising a tone-arm adapted to be supported upon the casing of a talking machine and comprising telescopic portions, whereby one of said portions may be moved in a longitudinal direction relatively to the other thereof to vary the length of the tone-arm, a sound-box carried by said movable portion, said movable portion being rotatable independently of its longitudinal movement when in either of its adjusted positions, whereby said sound-box may be inverted to permit the insertion or removal of a stylus when said movable member is in either of its adjusted positions, and means to limit the rotary movement of said movable portion, substantially as specified.

3. A device of the character described comprising a tone-arm adapted to be supported upon the casing of a talking machine and comprising telescopic portions, whereby one of said portions may be moved in a

longitudinal direction relatively to the other thereof to vary the length of the tone-arm, a sound-box carried by said movable portion, said movable portion being rotatable independently of its longitudinal movement when in either of its adjusted positions, whereby said sound-box may be inverted to permit the insertion or removal of a stylus when said movable member is in either of its adjusted positions, and means for limiting the longitudinal and the rotary movements of said movable portion, substantially as specified.

4. A device of the character described comprising a tone-arm adapted to be supported upon the casing of a talking machine and comprising telescopic portions, one of said portions being rotatable with respect

to the other thereof, one of said portions being provided with a longitudinally extending slot having circumferentially extending slots communicating with the ends thereof, the other of said portions being provided with means engaging said slots to limit the telescopic and rotary movements thereof, and a sound-box carried by one of said portions, substantially as specified.

Signed at the city of New York, in the county and State of New York, this 2nd day of August, one thousand nine hundred and sixteen.

EDGAR J. SPEER.
